COMB WITH SELF-CONTAINED CURLING DEVICE

Walter Raphael, New York, N. Y., assignor to
General Patent Production Company, New
York County, N. Y., a firm

Application June 12, 1952, Serial No. 293,062

1 Claim. (Cl. 132—11)

1

This invention relates to a comb with a self-contained hair curling device of the type used by women.

It is well known that curly or wavy hair is greatly desired by womankind but unfortunately nature does not bestow this type of hair upon all womankind. The permanent wave or the home hair curler is therefore required by most women.

Unfortunately, however, curling devices which are presently upon the market are bulky and cumbersome.

It is an object of this invention to provide a curling device which may be used in connection with a comb and which will disappear within said comb when not required.

It is a further object of this invention to provide a curling device which will retract into the body of a comb automatically.

Briefly stated the invention comprises a comb with a hollow handle member and a plurality of spaced teeth depending from the handle member. In the preferred modification of this invention a horizontal slot is provided in the top portion of the handle member. A curling device, which is preferably a pointed rod member is disposed within the hollow handle member and an additional handle member is secured to the hollow handle member and extends through said slot. A spring member is disposed about the pointed rod member, one end of the spring being secured to the handle member and the other end to the additional handle member. In addition it is preferable to provide an additional slot in the front portion of the handle member communicating with the slot in the top portion of the handle member so that the rod member may be held in extended position when desired.

The invention will be further described by reference to the accompanying drawings which are made a part of this specification.

Fig. 1 is a front view, partly in section, showing the comb with a self-contained hair curling device made in accordance with this invention.

Fig. 2 is a front view, partly in section, showing a portion of the invention when the hair curling device is in extended position.

Fig. 3 is a front view of the invention showing the means that may be provided to temporarily secure the hair curling device in extended position.

Fig. 4 is a sectional view of the invention taken along line 4—4 of Fig. 1.

Fig. 5 is a sectional view of the invention taken along line 5—5 of Fig. 1.

2

There is provided comb 11 which is formed of handle member 12 and spaced teeth portions 13. Handle 12 is hollow having hole 14 disposed therein. Handle 12 is also provided with slot 15 communicating with hole 14 in the top portion thereof.

The curling device used in this invention is a rod member 16 bearing point 17 at the front end thereof. Additional handle 18 is secured to rod member 16 and is disposed within slot 15. Holding member 19 is secured to handle 18 so as to prevent disassembly of the device.

Spring 20 is disposed about rod member 16 and is made of wide coils. One end 21 of spring 20 is secured to handle 18 while the other end 22 of spring 20 is secured to the interior of handle 12.

Additional slot 23 is preferably provided in the front portion of handle 12. Slot 23 communicates with slot 15 and handle 18 may be placed into slot 23. Slot 23 is provided with offset extension 24 so as to removably hold handle 18 when rod member 16 is in extended position as will be subsequently explained.

With the description of this invention given 25 the operation of the device may now be set forth.

When it is desired to use the device as a comb only rod member 16 is in retracted position within handle 12 and is held in such position by the action of spring 20. When it is desired to use the curling device however handle 18 is grasped and drawn along slot 15 to the end thereof. This movement, however, is performed under tension since spring 20 is compressed.

When the curling device, i. e. rod member 16, is fully extended handle 18 is turned toward the front portion of the comb. It is pointed out that rod member 16 is capable of being turned within handle member 12.

When handle 18 is turned toward the front portion of the comb it is disposed in slot 23 which is connected to slot 15. Handle 18 is then let go and is then driven back into offset portion 24 by the action of spring 20. However since offset portion 24 extends only a short distance rearwardly handle 18 is firmly held in place and rod member 16 is held in extended position.

When it is desired to retract rod member 16 when the curling device is no longer used handle 18 is turned toward the top portion of handle 12 with a short push forward to re-engage the front portion of slot 23. Handle 18 is then let go and spring 20 pushes rod member 16 into handle 12.

The foregoing specific embodiments of this 55 invention as shown in the foregoing specification

are for illustrative purposes and for purposes of example only. Various changes and modifications of this invention can obviously be made within its spirit and scope and will occur to those skilled in this art.

I claim:

A comb comprising a hollow handle member, a plurality of spaced teeth depending from said handle member, said handle member being provided with a horizontal slot in the upper portion thereof communicating with the hollow portion of said handle member; an extensible pointed rod member adapted to be used as a curling device disposed within said handle member, an additional handle member secured to said rod member disposed within said slot, a spring member disposed about said rod member, one end of said spring member being secured to said additional handle member, the other end of said spring member being secured to said first-named

5

handle member, said spring member being compressed when said rod member is extended; said first-named handle member being also provided with an additional slot in the front portion there-

10

of communicating with said first-named slot and adapted to removably hold said last-named handle member to said first-named handle member when said rod member is in extended position.

WALTER RAPHAEL.

handle member, said spring member being compressed when said rod member is extended; said first-named handle member being also provided with an additional slot in the front portion there-

15

of communicating with said first-named slot and adapted to removably hold said last-named handle member to said first-named handle member when said rod member is in extended position.

WALTER RAPHAEL.
